FIG. 1 is a perspective view of a rotating message holder embodying the present design;

FIG. 2 is a top plan view of the rotating message holder shown in FIG. 1;

FIG. 3 is an elevational view of the side indicated by numeral 3 in FIG. 1;

FIG. 4 is an elevational view of the side indicated by numeral 4 in FIG. 1;

FIG. 5 is an elevational view of the side indicated by numeral 5 in FIG. 1; and

FIG. 6 is a bottom view of the device.

The L-shaped members extending from the top aperture are movable in relation to the housing and therefore

are shown in different positions in FIGS. 1, 2, 3, 4 and 5. The indicia is shown in FIG. 1 in broken lines for illustrative purposes only.

I claim:

The ornamental design for a rotating message holder, substantially as shown and described.
